United States Patent Office

Des. 193,325
Patented Aug. 7, 1962

193,325

INCINERATING TOILET

Donald P. Frankel, Walworth, Wis., assignor to La Mere Industries, Incorporated, Walworth, Wis., a corporation of Delaware

Filed Oct. 18, 1961, Ser. No. 67,150

Term of patent 14 years

(Cl. D4—5)

The figure is a front perspective view of an incinerating toilet showing my new design. The side not shown is substantially like the side shown. The rear is substantially plain.

I claim:

The ornamental design for an incinerating toilet, as shown and described.
